UNITED STATES PATENT OFFICE.

HELEN E. HOLLINGSWORTH, OF MINNEAPOLIS, MINNESOTA.

DOLL.

Application filed November 28, 1923. Serial No. 603,743.

To all whom it may concern:

Be it known that I, HELEN E. HOLLINGSWORTH, a citizen of the United States, residing in Minneapolis, in the county of 5 Hennepin and State of Minnesota, have invented a new and useful Doll, of which the following is a specification.

My invention relates to improvements in dolls.

10 One object is to provide an electric doll serving as an electric lighting novelty, the head comprising the electric lamp and the body the electric socket of a lighting fixture, said doll having arms adjustable angularly 15 on the socket to permit the placement thereof in proper relation with respect to the face of the doll when the lamp is seated in the socket.

With the foregoing and other objects in view, which will appear in the following description, the invention resides in the novel combination and arrangement of parts and in the details of construction herein-after described and claimed.

25 In the drawings, Fig. 1 is an elevation showing an embodiment of my invention, the same illustrating a doll attired in gown and hat; Fig. 2 is an elevation of the doll, the clothing being omitted and Fig. 3 is 30 a plan view in detail illustrating the arms of the doll and the socket or body to which the arms are attached, said socket being illustrated diagrammatically.

Referring to the drawings, it will be observed that my improved doll comprises essentially a base 10, an electric socket 11, an electric lamp 12 and arms 13. The base 10 supports the socket 11 in upright position, said socket being wired in a manner 40 common to lighting fixtures of similar type. The lamp 12 as shown, has a spherical, frosted bulb, the same being painted with heat resisting material to resemble a human head. I also contemplate the formation of 45 lamps simulating more closely the contour of the human head, the same to be variously tinted to correspond with different types of persons. The socket 11, supported on the base 10, comprises the body of the doll and 50 the lamp 12 the head thereof. The arms 13 are secured to a mounting 14 applied to the socket 11, said arms 13 having anchoring eyes 15 fastened in the shoulders thereof in accordance with the usual practice. The

mounting 14 is preferably a ring-like spiral 55 spring. This spring is placed in encircling relation about the socket 11 and against the annular shoulder 16 thereon, the tension in said spring causing the same to yieldingly grip the socket. The arms 13 are secured 60 to the spring or mounting 14 by catching the eyes 15 in diametrically opposed turns in said spring. In fitting different lamps in a socket, said lamps when seated will be found to take various angular positions 65 with respect to the socket. The adaptability of the mounting 14 to angular adjustment on the socket 11 provides for readily turning the arms into proper relation with respect to a head seated in said socket. It 70 will be understood therefore, that the arms 13 of the doll can be readily turned to accord with the position of the face. The doll is conveniently attired as by a dress 75 16 and hat 17, the latter supplying a shade for the lamp 12. The hat frame is similar in construction to the frame of the ordinary lamp shade and like the dress can be made very attractive in various pleasing and artistic designs.

Changes in the specific form of my invention, as herein disclosed, may be made within the scope of what is claimed without departing from the spirit of my invention.

Having described my invention, what I 85 claim as new and desire to protect by Letters Patent is:

1. A doll of the class described including, in combination, an electric socket having an annular shoulder thereon and comprising 90 the body of the doll, means supporting said socket in upright position, an electric lamp fitted in said socket and comprising the head of the doll, a flexible mounting encircling and yieldingly gripping the socket, 95 said mounting being held against downward displacement by engagement with the shoulder on said socket, and arms secured to the mounting, said mounting being adjustable angularly of said socket to permit the 100 proper positioning of said arms with respect to said head.

2. A doll of the class described including, in combination, an electric socket comprising 105 the body of the doll, means supporting said socket in upright position, an electric lamp fitted in said socket and comprising the head of the doll, a mounting encircling

the socket and arms secured to the mounting, said mounting being adjustable angularly of the socket to permit the proper positioning of the arms with respect to said head.

3. A doll of the class described including, in combination, an electric socket, means for supporting the socket, said socket comprising the body of the doll, an electric lamp fitted in said socket and comprising the head of the doll, and arms mounted on the socket and adjustable angularly thereof

to permit the proper positioning of said arms with respect to the head.

4. A doll of the present nature including a body, a head removably fitted on said body and arms mounted on the body and movable about the axis thereof to permit of the appropriate placement of said arms with respect to the head.

In testimony whereof, I have signed my name to this specification.

HELEN E. HOLLINGSWORTH.
